4-ARYL, 4-ALKARYL-5-OXOHEXANOIC ACID
Everett M. Schultz, Ambler, and Edward J. Cragoe, Jr.,
Lansdale, Pa., assignors to Merck & Co., Inc., Rahway,
N.J., a corporation of New Jersey
No Drawing. Filed July 15, 1954, Ser. No. 443,695
6 Claims. (Cl. 260—515)

This invention is broadly concerned with 4,4-disubstituted-5-oxohexanoic acids and derivatives thereof. It is more particularly concerned with new 4-aryl-4-aralkyl-5-oxohexanoic acids.

The compounds of this invention can be represented by the general formula

in which R is an aryl radical, either unsubstituted or substituted, and R' is an aralkyl radical, also either unsubstituted or substituted, particularly in the aryl moiety of the radical. Salts, esters, enol-lactones and amides of the above compounds are also contemplated within the scope of this invention as they are considered to be the equivalents of the acids because many of the derivatives exhibit the same therapeutic activity as the corresponding acid. It is hypothesized that the activity exhibited by the derivatives results from their conversion to the corresponding acid upon administration and that the free acid actually produces the therapeutic effect observed. As there is little difference therapeutically whether the acid, salt, ester, enol-lactone or amide is administered, all of these compounds are equivalent for the purpose of this invention. As the derivatives often have a different fate in the body as compared with the acid, it may be more advantageous to employ a salt, ester, enol-lactone or amide rather than the free acid because the derivative will often release the active form of the compound more slowly and certain of them will release the active form at a more advantageous site.

The ester, enol-lactone and amide derivatives will be described in more detail hereinafter. The only limitation to the type of salt is that it be non-toxic. Both water soluble and water insoluble salts are useful, depending upon the purpose for which salts of the compounds are to be employed. Insoluble salts are sometimes most useful when it is desired to take advantage of the repository effects produced by compounds of this type, whereas soluble salts, especially water soluble salts, are usually better suited for use in oral preparations and other dosage forms designed for more rapid absorption into the blood stream.

It will be seen from the foregoing structural formula that all of the compounds of this invention contain an asymmetric carbon atoms, that is, the 4-position carbon atom to which the variable radicals R and R' are attached. This is true not only of the hexanoic acids but also of the hexanenitrile intermediates and of each of the derivatives of the hexanoic acids hereinafter described. Because of the presence of this asymmetric carbon atom in the molecule, the racemic modification of the various products are obtained as the end products of the syntheses described. The optically active isomers can be separated by well known methods, if desired, and these individual antipodes can be employed to make subsequent derivatives having the same optical configuration if this is desired.

The compounds of this invention have utility as therapeutic agents, for example, as bactericidal, bacteriostatic, virucidal, and virustatic agents. Some of the novel compounds have shown marked activity as virustatic agents, particularly against organisms causing virus infections in the respiratory tract of man and animals.

Among the compounds having the general Formula 1, those wherein R is a phenyl radical and R' is a benzyl radical have been found generally to have better virustatic

2

activity, and when R is the phenyl radical and R' is a substituted benzyl radical, the virustatic activity appears to be enhanced markedly.

Substituents suitable for attachment to the aryl portion of the phenyl and/or the benzyl radical are halogens, e.g., chlorine, bromine, iodine or fluorine; lower alkyl, e.g., methyl, ethyl, propyl and the like; lower alkoxy, as methoxy, ethoxy, propoxy; nitro; carboxy; hydroxy; and hydroxy-alkyl groups. The phenyl and/or the benzyl radicals can be substituted in the nuclear portion of either or both of them in ortho-, meta- or para-position, and mono- or poly-substitution can be made in either or both of these radicals. When each of the aryl and aralkyl groups is mono- or poly-substituted, or when either is poly-substituted, the substituents need not necessarily be the same. Any combination of substitution is suitable so long as it is chemically possible to introduce the selected radicals into the same nucleus. Ortho-substitution, particularly solely in the aryl portion of the benzyl radical, generally produces compounds having a high order of virustatic activity and, surprisingly, ortho-halogen substitution substantially increases the virustatic activity of these compounds. Especially marked virustatic activity is exhibited by the compound 4-(ortho-chlorobenzyl)-4-phenyl-5-oxohexanoic acid particularly against the PR8 strains of influenza. This compound, as well as others embraced by this invention, is also effective against other strains of influenza virus as well as other viruses such as the infectious agent in mumps.

30 The compounds generally, and in particular 4-(ortho-chlorobenzyl)-4-phenyl-5-oxohexanoic acid, are effective upon oral administration. This is a distinct advantage especially in the treatment of virus infections of the upper respiratory tract. Administration is not restricted to the oral route, however, as the compounds can be administered parenterally if this is indicated.

The compounds of this invention are prepared by alkylation of phenylacetone or a nuclearly substituted derivative thereof to introduce the desired benzyl radical. 40 Reaction readily occurs at the carbon atom which carries the phenyl radical. Cyanoethylation of the end product thus obtained produces the corresponding 4-phenyl-4-benzyl-5-oxohexanenitrile which, on hydrolysis, is converted to the desired 4-phenyl-4-benzyl-5-oxohexanoic acid. The individual reaction procedures are those conventionally employed to effect the same type of substitution in other compounds.

The salts and the ester, amide and enol-lactone derivatives are all prepared by known procedures.

In general, the salts are prepared by the action of an alkali metal hydroxide, an alkali metal carbonate or bicarbonate, an amine or ammonia or the like on the oxohexanoic acid.

50 The ester derivatives are readily prepared by allowing the selected 4-aryl-4-aralkyl-5-oxohexanoic acid to react with the appropriate alcohol in the presence of esterification catalysts, such as certain mineral acids, e.g., sulfuric acid.

The enol-lactone derivatives are prepared advantageously by interaction of the selected hexanoic acid with isopropenyl acetate.

55 Basic esters generally are prepared by reacting the enol-lactone with a (di-substituted-amino)-alkanol.

And the amides advantageously are prepared by allowing the selected enol-lactone to react with the desired amine preferably with heating under reflux conditions.

60 The general method by which the compounds of this invention are prepared can be illustrated by the following reaction formulae:

70

The elements R and R' in the above formulae have the meaning assigned to each of them above, R'', R''' and R'''' respectively is an alkyl radical, advantageously a lower alkyl radical, and X is halogen or a similarly reactive radical, e.g., a sulfonate ester radical and the like. Substantially all of the compounds illustrated by the structures identified by A to G above are new compounds.

Where the starting nucleophilic substituted phenylacetone is unknown or not readily obtainable commercially, a suitable method for preparing it consists in condensing a benzaldehyde having the desired substituent on the phenyl nucleus with nitroethane, then reducing and simultaneously hydrolyzing the resulting 1-(substituted-phenyl)-2-nitropropene using iron and aqueous hydrochloric acid. Another method which can be employed in preparing the nucleophilic substituted phenylacetones consists in heating a phenylacetic acid having the desired substituent or substituents attached to the phenyl nucleus with sodium acetate and acetic anhydride. Other methods may be more suitable depending upon the substituent or substituents one desires to have attached to the phenyl nucleus. All of these other methods are well known and would readily suggest themselves to a chemist desiring to prepare a particular nucleophilic substituted phenylacetone.

The novel compounds of this invention are also useful as intermediates in preparing derivatives which have been found to have therapeutic activity. Derivatives of particular interest in this respect are the heretofore unknown 4-aryl-4-alkyl-1,3-cyclohexanediones. These compounds are often formed as by-products when the 4-aryl-4-alkyl-5-oxohexanenitriles are hydrolyzed to the corresponding acid. They can also be prepared from an ester of the 4-aryl-4-alkyl-5-oxohexanoic acid which is readily converted to the 1,3-cyclohexanedione derivative in the presence of a basic catalyst. Another method has been discovered for the preparation of these compounds in good yields. According to this method, the 1-aryl-1-alkyl-2-propanones (compounds A in the preceding reaction schemes) are allowed to react with beta-propio-

lactone in the presence of a condensing agent. This novel method is another feature of this invention.

Details of the preparation of the compounds of this invention as well as the preparation of representative derivatives are contained in the following examples, which are illustrative and in no wise limit the procedures by which they can be prepared to the particular steps described. All physical constants are uncorrected values.

A. PREPARATION OF 1-ARYL-1-ARALKYL-2-PROPANONES

Example 1.—1-(o-chlorobenzyl)-1-phenyl-2-propanone.—Flake sodium hydroxide of about 90% purity (89 g., ca. 2 moles) was placed in a one-liter, four-necked, round-bottom flask equipped with a mechanical stirrer, dropping funnel, thermometer, and condenser protected with a soda-lime drying tube. Phenylacetone (201.5 g., 1.5 mole) and o-chlorobenzyl chloride (282 g., 1.75 mole) were thoroughly mixed and approximately 100 ml. of the mixture added to the reaction vessel with vigorous stirring. The temperature rose to 55–60° C. The reaction mixture was heated on a steam bath to 70° C., and the ketone-

halide mixture added dropwise at a rapid rate. The temperature rose to 90–95° C. and remained there about 15 minutes as addition was continued. The temperature then began to fall, even though addition was continued; therefore, the reaction vessel was heated on a steam bath in order to maintain a temperature of 90–100° C. Total addition time was 35 minutes.

After addition was complete, the mixture was stirred and heated on a steam bath for 9 hours. The mixture then was cooled and treated with water (200 ml.) and benzene (1200 ml.). The mixture was stirred and acidified with concentrated hydrochloric acid. The layers were separated and the aqueous phase washed three times with 50 ml. portions of benzene and the aqueous phase discarded. The benzene extracts were combined with the original organic phase and dried over anhydrous sodium sulfate. After drying, the benzene was removed by reduced pressure distillation (water aspirator) and the residue fractionated in vacuo. A total of 308 g. (79%) of 1-(o-chlorobenzyl)-1-phenyl-2-propanone, boiling at 145–150° C. at 1.5 mm. pressure, was collected ($n_D^{25}=1.5681$). Refractionation gave a very good recovery of this product, B.P. 154–156° C. at 2.3 mm. pressure ($n_D^{25}=1.5679$).

Example 2.—1-(o-bromobenzyl)-1-phenyl-2-propanone.—Potassium (31.6 g., 0.81 mole) was added to sodium-dried tertiary-butyl alcohol (700 ml.) in a two-liter, four-necked, round-bottom flask equipped with a mechanically driven Hirshberg stirrer, dropping funnel, thermometer, and reflux condenser. The potassium was dissolved by warming and violently agitating the mixture. The mixture was cooled and phenylacetone (108.8 g., 0.81 mole) was added in one portion. o-Bromobenzyl bromide (214.5 g., 0.86 mole) was dissolved in dry benzene (100 ml.) and the mixture added dropwise over a period of 40 minutes, while the temperature was maintained at 35–40° C. The reaction mixture was stirred an additional 10 minutes without the application of heat, and then it was refluxed for an hour and 50 minutes.

The solvent then was removed by distillation at reduced pressure and the residue treated with benzene (200 ml.) and water (200 ml.). The two layers were separated, and the aqueous layer was washed with benzene (50 ml.). The organic layers were combined and dried over sodium sulfate, and the solvent was removed by distillation. Fractional distillation of the residue at reduced pressure gave 205.3 g. (84%) of 1-(o-bromobenzyl)-1-phenyl-2-propanone, B.P. 164-170° C. at 0.1 mm. pressure. Refractionation gave 1-(o-bromobenzyl)-1-phenyl-2-propanone, B.P. 166-170° C. at 0.1 mm. pressure ($n_D^{25}=1.5838$).

Example 3. — 1-(o-chlorobenzyl)-1-(o-chlorophenyl)-2-propanone.—By replacing the phenylacetone and o-bromobenzyl bromide reactants employed in Example 2 by o-chlorophenylacetone and o-chlorobenzyl chloride respectively, and following the same procedure described in Example 2, there was obtained a 78% yield of 1-(o-chlorobenzyl)-1-(o-chlorophenyl)-2-propanone, B.P. 161-165° C. at 0.1 mm. pressure ($n_D^{25}=1.5762$).

Example 4. — 1-(3,4-dichlorobenzyl)-1-(4-chlorophenyl)-2-propanone.—By replacing the phenylacetone and the o-bromobenzyl bromide reactants employed in Example 2 by p-chlorophenylacetone and 3,4-dichlorobenzyl chloride respectively, and following substantially the same procedure described in Example 2, there was obtained 1-(3,4-dichlorobenzyl)-1-(4-chlorophenyl)-2-propanone.

Example 5. — 1-benzyl-1-(3,4-dichlorophenyl)-2-propanone.—By replacing the phenylacetone and the o-bromobenzyl bromide reactants in Example 2 by 3,4-dichlorophenylacetone and benzyl chloride respectively, and following substantially the same procedure described in Example 2, there was obtained 1-benzyl-1-(3,4-dichlorophenyl)-2-propanone.

Example 6. — 1-(2,4,6-trimethylbenzyl)-1-phenyl-2-propanone.—By replacing the o-bromobenzyl bromide reactant employed in Example 2 by 2,4,6-trimethylbenzyl chloride, and following substantially the same procedure described in Example 2, there was obtained an 81% yield of 1-(2,4,6-trimethylbenzyl)-1-phenyl-2-propanone, B.P. 160-165° C. at 0.3 mm. pressure, M. P. 58-60° C.

Example 7. — 1-(3,4,5-trichlorobenzyl)-1-phenyl-2-propanone.—By replacing the o-bromobenzyl bromide reactant employed in Example 2 by 3,4,5-trichlorobenzyl chloride (prepared by chlorination of the corresponding toluene), and following substantially the same procedure described in Example 2, there was obtained 1-(3,4,5-trichlorobenzyl)-1-phenyl-2-propanone.

Example 8. — 1-(p-propylbenzyl)-1-phenyl-2-propanone.—By replacing the o-bromobenzyl bromide reactant employed in Example 2 by p-propylbenzyl chloride (prepared by chloromethylation of propylbenzene), and following substantially the same procedure described in Example 2, there was obtained 1-(p-propylbenzyl)-1-phenyl-2-propanone.

Example 9. — 1-(chlorobenzyl)-1-(p-ethylphenyl)-2-propanone.—By replacing the phenylacetone and the o-bromobenzyl bromide reactants employed in Example 2 by p-ethylphenylacetone and p-chlorobenzyl chloride respectively, and following substantially the same procedure described in Example 2, there was obtained 1-(p-chlorobenzyl)-1-(p-ethyl)-2-propanone.

Example 10. — 1-(o-chlorobenzyl)-1-(p-methoxyphenyl)-2-propanone.—By replacing the phenylacetone and the o-bromobenzyl bromide employed in Example 2 by p-methoxyphenylacetone and o-chlorobenzyl chloride respectively, and following substantially the same procedure described in Example 2, there was obtained 1-(o-chlorobenzyl)-1-(p-methoxyphenyl)-2-propanone.

Example 11. — 1-(p-ethoxybenzyl)-1-(m-methoxyphenyl)-2-propanone.—By replacing the phenylacetone and the o-bromobenzyl bromide reactants employed in Example 2 by m-methoxyphenylacetone and p-ethoxybenzyl chloride (prepared by reducing p-ethoxybenzaldehyde to p-ethoxybenzyl alcohol followed by treatment with anhydrous hydrogen chloride to produce p-ethoxybenzyl chloride) respectively, and following substantially the same procedure described in Example 2, there was obtained 1-(p-ethoxybenzyl)-1-(m-methoxyphenyl)-2-propanone.

Example 12. — 1-(m-methylbenzyl)-1-(o-methoxyphenyl)-2-propanone.—By replacing the phenylacetone and the o-bromobenzyl bromide reactants employed in Example 2 by o-methoxyphenylacetone and m-methylbenzyl chloride respectively, and following substantially the same procedure described in Example 2, there was obtained 1-(m-methylbenzyl)-1-(o-methoxyphenyl)-2-propanone.

Example 13. — 1-benzyl-1-(o-chlorophenyl)-2-propanone.—By replacing the phenylacetone and the o-bromobenzyl bromide reactants employed in Example 2 by o-chlorophenylacetone and benzyl chloride respectively, and following substantially the same procedure described in Example 2, there was obtained a 93% yield of 1-benzyl-1-(o-chlorophenyl)-2-propanone, B.P. 150-155° C. at 0.3 mm. pressure ($n_D^{25}=1.5682$).

Other 1-aryl-1-aralkyl-2-propanones, prepared by the process described in Examples 1 and 2, are identified in Table I. In each instance the alkylating agent, R'X, identified in the 3rd column of the table, was allowed to react with phenylacetone, thus forming a 1,1-disubstituted ketone having the structure

55 wherein R' is the radical identified in column 4.

B. PREPARATION OF 4,4-DISUBSTITUTED-5-OXOHEXANENITRILES

Example 25. — 4-(*o*-chlorobenzyl)-4-phenyl-5-oxohexanenitrile. — 1-(*o*-chlorobenzyl)-1-phenyl-2-propanone (456 g., 1.76 mole), prepared as described in Example 1, was dissolved in tertiary-butyl alcohol (1200 ml.) in a three-liter, three-necked, round-bottom flask fitted with a mechanical stirrer and dropping funnel. The catalyst, benzyltrimethylammonium hydroxide (20 ml. of 40% aqueous solution), was added. Acrylonitrile (112 g., 2.12 moles) then was added via a dropping funnel over a period of 10 minutes while the solution was stirred and cooled so that the temperature remained below 30° C. Stirring was continued for 2 hours at room temperature and then 1 hour at 38-45° C. A periodic check on the pH of the reaction mixture was made to be sure that alkaline conditions were maintained. If the solution was not strongly alkaline throughout the reaction, more catalyst was added. The mixture was neutralized with sulfuric acid and the solid removed by filtration. It is advisable to wash the product on the funnel with a small amount of cold isopropyl alcohol. The yield of dry 4-(*o*-chlorobenzyl)-4-phenyl-5-oxohexanenitrile was 491 g. (90%), M.P. 103-106° C. Recrystallization of the crude material from isopropyl alcohol (1500 ml.) gave 467 gm. (85%) of product, M.P. 104.5-107° C. Further recrystallization gave material melting at 106-108° C.

The above procedure has been found to be most suitable for the preparation of the hexanenitrile compounds. Minor modifications have been made in order to provide the optimum reaction conditions for cyanoethylation of any one particular ketone. For example, when more drastic reaction conditions are required to cyanoethylate a hindered ketone, the temperature is increased up to refluxing conditions, and the tertiary-butyl alcohol is replaced by acetonitrile or 1,4-dioxane and the quaternary ammonium catalyst replaced by potassium hydroxide. The product may separate from the reaction mixture as a solid in good yields as described in Example 25 and it then is readily isolated and purified as indicated. In all other case the following modifications are made: When the reaction is complete, the catalyst is neutralized with acid, the solvent removed by distillation under reduced pressure, and the 4-aryl-4-aryl-5-oxohexanenitrile recovered by recrystallization when it is a solid or by distillation when it is a liquid. These modifications are well known to a chemist and are described here in order to minimize the amount of detailed description in the following examples. While each of the following examples describe the preparation of a particular compound according to the process described in Example 25, it is to be understood that the above modifications were made when necessary.

Example 26.—4-(3,4-dichlorobenzyl)-4-(4-chlorophenyl)-5-oxohexanenitrile.—By replacing the 1-(o-chlorobenzyl)-1-phenyl-2-propanone employed in Example 25 by an equimolecular quantity of 1-(3,4-dichlorobenzyl)-1-(4-chlorophenyl)-2-propanone, prepared as described in Example 4, and following substantially the same procedure described in Example 25, there was obtained 4-(3,4-dichlorobenzyl)-4-(4-chlorophenyl)-5-oxohexanenitrile.

Example 27.—4-benzyl-4-(3,4-dichlorophenyl)-5-oxohexanenitrile.—By replacing the 1-(o-chlorobenzyl)-1-phenyl-2-propanone employed in Example 25 by an equimolecular quantity of 1-benzyl-1-(3,4-dichlorophenyl)-2-propanone, prepared as described in Example 5, and following substantially the same procedure described in Example 25, there was obtained 4-benzyl-4-(3,4-dichlorophenyl)-5-oxohexanenitrile.

Example 28.—4-(3,4,5-trichlorobenzyl)-4-phenyl-5-

oxohexanenitrile.—By replacing the 1-(o-chlorobenzyl)-1-phenyl-2-propanone employed in Example 25 by an equimolecular quantity of 1-(3,4,5-trichlorobenzyl)-1-phenyl-2-propanone, prepared as described in Example 7, and following substantially the same procedure described in Example 25, there was obtained 4-(3,4,5-trichlorobenzyl)-4-phenyl-5-oxohexanenitrile.

Example 29.—4-(*p*-propylbenzyl)-4-phenyl-5-oxohexanenitrile.—By replacing the 1-(*o*-chlorobenzyl)-1-phenyl-2-propanone employed in Example 25 by an equimolecular quantity of 1-(*p*-propylbenzyl)-1-phenyl-2-propanone, prepared as described in Example 8, and following substantially the same procedure described in Example 25, there was obtained 4-(*p*-propylbenzyl)-4-phenyl-5-oxohexanenitrile.

Example 30.—4-(p-chlorobenzyl)-4-(p-ethylphenyl)-5-oxohexanenitrile.—By replacing the 1-(o-chlorobenzyl)-1-phenyl-2-propanone employed in Example 25 by an equimolecular quantity of 1-(p-chlorobenzyl)-1-(p-ethylphenyl)-2-propanone, prepared as described in Example 9, and following substantially the same procedure described in Example 25, there was obtained 4-(p-chlorobenzyl)-4-(p-ethylphenyl)-5-oxohexanenitrile.

Example 31.—4-(*o*-chlorobenzyl)-4-(*p*-methoxyphenyl)-5-oxohexanenitrile.—By replacing the 1-(*o*-chlorobenzyl)-1-phenyl-2-propanone employed in Example 25 by an equimolecular quantity of 1-(*p*-ethoxybenzyl)-1-methoxyphenyl)-2-propanone, prepared as described in Example 10, and following substantially the same procedure described in Example 25, there was obtained 4-(*o*-chlorobenzyl)-4-(*p*-methoxyphenyl)-5-oxohexanenitrile.

Example 32.—4-(*p*-ethoxybenzyl)-4-(*m*-methoxyphenyl)-5-oxohexanenitrile.—By replacing the 1-(*o*-chlorobenzyl)-1-phenyl-2-propanone employed in Example 25 by an equimolecular quantity of 1-(*p*-ethoxybenzyl)-1-(*m*-methoxyphenyl)-2-propanone, prepared as described in Example 11, and following substantially the same procedure described in Example 25, there was obtained 4-(*p*-ethoxybenzyl)-4-(*m*-methoxyphenyl)-5-oxohexanenitrile.

Example 33.—4-(*m*-methylbenzyl)-4-(*o*-methoxyphenyl)-5-oxohexanenitrile.—By replacing the 1-(*o*-chlorobenzyl)-1-phenyl-2-propanone employed in Example 25 by an equimolecular quantity of 1-(*m*-methylbenzyl)-1-(*o*-methoxyphenyl)-2-propanone, prepared as described in Example 12, and following substantially the same procedure described in Example 25, there was obtained 4-(*m*-methylbenzyl)-4-(*o*-methoxyphenyl)-5-oxohexanenitrile.

50 Other 4-aryl-4-alkyl-5-oxohexanenitriles, prepared by the process described in Example 25, are identified in Table II. In each instance the 1-(o-chlorobenzyl)-1-phenyl-2-propanone employed in Example 25 was replaced by a ketone having the formula

which was allowed to react with acrylonitrile by substantially the same procedure described in Example 25, 65 thus yielding a hexanenitrile having the formula

The radicals R and R' in the starting ketone in each case are retained in the hexanenitrile end product and are identified in columns 2 and 3 of Table II.

C. PREPARATION OF 4-ARYL-4-ARALKYL-5-OXOHEXANOIC ACIDS

As indicated previously, the hexanenitriles of this invention contain an asymmetric carbon atom; therefore the racemic modification is produced in the synthesis. Hydrolysis of these hexanenitriles produces the corresponding racemic modification of the hexanoic acids. The following example describes a preferred method for hydrolyzing the hexanenitriles to the DL-hexanoic acids.

Example 49.—4-(o-chlorobenzyl)-4-phenyl-5-oxohexanoic acid.—4-(o-chlorobenzyl)-4-phenyl-5-oxohexanenitrile (412.5 g., 1.32 mole), prepared as described in Example 25, concentrated sulfuric acid (450 ml.), glacial acetic acid (2 liters) and water (600 ml.) were placed in a five-liter, round-bottom flask and refluxed for 1 and 1/4 hours. A sample of the reaction mixture was completely soluble in excess alkali. The mixture was poured with stirring into cold water (8 liters). An oil separated which solidified upon stirring. The solid was filtered off, washed with water, dried, and pulverized; 415 g. (97%) of 4-(o-chlorobenzyl)-4-phenyl-5-oxohexanoic acid, M.P. 106-125° C., was obtained. One recrystallization from acetonitrile (830 ml.) gave 354 gm. (81%), M.P. 124-130° C. Further recrystallization gives material melting at 132-134° C.

Example 50.—4-(3,4-dichlorobenzyl)-4-(4-chlorophenyl)-5-oxohexanoic acid.—By replacing the 4-(o-chlorobenzyl)-4-phenyl-5-oxohexanenitrile employed in Example 49 by an equimolecular quantity of 4-(3,4-dichlorobenzyl)-4-(4-chlorophenyl)-5-oxohexanenitrile, prepared as described in Example 26, and following substantially the same procedure described in Example 49, there was obtained 4-(3,4-dichlorobenzyl)-4-(4-chlorophenyl)-5-oxohexanoic acid.

Example 51.—4-benzyl-4-(3,4-dichlorophenyl)-5-oxohexanoic acid.—By replacing the 4-(o-chlorobenzyl)-4-phenyl-5-oxohexanenitrile employed in Example 49 by an equimolecular quantity of 4-benzyl-4-(3,4-dichlorophenyl)-5-oxohexanenitrile, prepared as described in Example 27, and following substantially the same procedure described in Example 49, there was obtained 4-benzyl-4-(3,4-dichlorophenyl)-5-oxohexanoic acid.

Example 52.—4-(3,4,5-trichlorobenzyl)-4-phenyl-5-oxohexanoic acid.—By replacing the 4-(o-chlorobenzyl)-4-phenyl-5-oxohexanenitrile employed in Example 49 by an equimolecular quantity of 4-(3,4,5-trichlorobenzyl)-4-phenyl-5-oxohexanenitrile, prepared as described in Example 28, and following substantially the same procedure described in Example 49, there was obtained 4-(3,4,5-trichlorobenzyl)-4-phenyl-5-oxohexanoic acid.

Example 53.—4-(p-propylbenzyl)-4-phenyl-5-oxohex-

anoic acid.—By replacing the 4-(o-chlorobenzyl)-4-phenyl-5-oxohexanenitrile employed in Example 49 by an equimolecular quantity of 4-(p-propylbenzyl)-4-phenyl-5-oxohexanenitrile, prepared as described in Example 29, and following substantially the same procedure described in Example 49, there was obtained 4-(p-propylbenzyl)-4-phenyl-5-oxohexanoic acid.

Example 54.—4-(p-chlorobenzyl)-4-(p-ethylphenyl)-5-oxohexanoic acid.—By replacing the 4-(o-chlorobenzyl)-4-phenyl-5-oxohexanenitrile employed in Example 49 by an equimolecular quantity of 4-(p-chlorobenzyl)-4-(p-ethylphenyl)-5-oxohexanenitrile, prepared as described in Example 30, and following substantially the same procedure described in Example 49, there was obtained 4-(p-chlorobenzyl)-4-(p-ethylphenyl)-5-oxohexanoic acid.

Example 55.—4-(o-chlorobenzyl)-4-(p-methoxyphenyl)-5-oxohexanoic acid.—By replacing the 4-(o-chlorobenzyl)-4-phenyl-5-oxohexanenitrile employed in Example 49 by an equimolecular quantity of 4-(o-chlorobenzyl)-4-(p-methoxyphenyl)-5-oxohexanenitrile, prepared as described in Example 31, and following substantially the same procedure described in Example 49, there was obtained 4-(o-chlorobenzyl)-4-(p-methoxyphenyl)-5-oxohexanoic acid.

Example 56.—4-(p-ethoxybenzyl)-4-(m-methoxyphenyl)-5-oxohexanoic acid.—By replacing the 4-(o-chlorobenzyl)-4-phenyl-5-oxohexanenitrile employed in Example 49 by an equimolecular quantity of 4-(p-ethoxybenzyl)-4-(m-methoxyphenyl)-5-oxohexanenitrile, prepared as described in Example 32, and following substantially the same procedure described in Example 49, there was obtained 4-(p-ethoxybenzyl)-4-(m-methoxyphenyl)-5-oxohexanoic acid.

Example 57.—4-(m-methylbenzyl)-4-(o-methoxyphenyl)-5-oxohexanoic acid.—By replacing the 4-(o-chlorobenzyl)-4-phenyl-5-oxohexanenitrile employed in Example 49 by an equimolecular quantity of 4-(m-methylbenzyl)-4-(o-methoxyphenyl)-5-oxohexanenitrile, prepared as described in Example 33, and following substantially the same procedure described in Example 49, there was obtained 4-(m-methylbenzyl)-4-(o-methoxyphenyl)-5-oxohexanoic acid.

Other hexanoic acids, prepared by hydrolyzing the hexanenitriles described in the preceding examples by the process described in Example 49, are identified in Table III. The radicals R and R' in the starting hexanenitrile in most cases are retained in the corresponding hexanoic acid end product and are identified in columns 2 and 3 in Table III. An exception occurs when either or both of the radicals R and R' contain a group, such as a cyano group, which is hydrolyzed under the conditions described in Example 49.

Table III

Ex. No.	R	R'	Hexanenitrile of Example No.	Reaction time, hours	Recrystallization solvent	M.P. ° C.
58	Phenyl	Benzyl	34	1	Isopropyl alcohol	143 -144.5
59	do	o-Methoxy-benzyl	43	2	Benzene + hexene, toluene + heptane, then acetic acid + H ₂ O	110 -113
60	do	o-Methyl-benzyl	41	1 1/2	Benzene + hexane, then acetic acid + H ₂ O	115 -117
61	do	m-Methyl benzyl	40	1 1/2	Cyclohexane, then ethyl acetate + cyclohexane	122.5 -124
62	do	p-Chlorobenzyl	35	2	Acetonitrile	131 -132.5
63	do	o-Fluorobenzyl	36	1	do	165 -167
64	do	3,4-dichlorobenzyl	37	1	Cyclohexane, then carbon tetrachloride	117.5 -119
65	do	2,4-dichlorobenzyl	38	1	Acetonitrile, then toluene	147 -148.5
66	do	2,6-dichlorobenzyl	39	1	Toluene, then acetic acid, then ethyl acetate	164.5 -166
67	do	m-Carboxybenzyl	144	2	Acetic acid, then n-butanol	239 -241
68	do	m-Chlorobenzyl	45	1	Acetonitrile	119 -121
69	do	o-Bromobenzyl	46	1	do	122 -123.5
70	o-Chlorophenyl	o-Chlorobenzyl	47	1	do	179.5 -181.5
71	do	Benzyl	48	1	do	185 -187

¹ R' is m-cyanobenzyl in the hexanenitrile.

The following examples are illustrative of suitable methods for separating the racemic modification to recover the levo- and the dextro-forms of the hexanoic acids. As all of the racemic compounds described in Examples 49 through 71 can be separated by the methods described below or by other well known methods, only a few representative experiments are described in detail.

Example 72.—*Levo-4-(o-chlorobenzyl)-4-phenyl-5-oxohexanoic acid.*—Racemic-4-(o-chlorobenzyl)-4-phenyl-5-oxohexanoic acid (354.4 g., 1.07 mole), prepared as described in Example 49, and brucine alkaloid (422.6 g., 1.07 mole) were dissolved in warm methanol, seeded, and cooled for 24 hours at room temperature and then 24 hours at 5° C. The solid was filtered off and dried. (The methanolic mother liquor was set aside for recovery, by the process described in Example 73, of the dextro-acid which remains in solution.) The yield was 351 g. of a solvate of the brucine salt of levo-4-(o-chlorobenzyl)-4-phenyl-5-oxohexanoic acid, M.P. 97-101° C. One recrystallization from methanol gave 300 g., M.P. 100-102° C. Two recrystallizations gave 289 g., M.P. 100-102° C. Analysis indicates that this salt is solvated. Using calculations that adjust for the solvation, the specific rotation of pure brucine salt is about -87.9° for a 2% solution in 95% ethanol at 25° C. The levo-acid brucine salt was dissolved in chloroform (1 liter) and extracted with an excess of aqueous sodium hydroxide solution (1 liter containing 20 g., 0.5 mole, of sodium hydroxide). Two more extractions of the chloroform phase with 100 ml. portions of aqueous sodium hydroxide of the same strength were made. The combined aqueous extracts were treated with benzene (500 ml.) and acidified with excess concentrated hydrochloric acid. The mixture was shaken and the aqueous phase removed and twice extracted with 100 ml. portions of benzene. The combined benzene layers were extracted with aqueous sodium hydroxide (1 liter containing 20 g., 0.5 mole, of sodium hydroxide). A second extraction with 200 ml. of aqueous sodium hydroxide of the same strength was made. The combined aqueous phases were treated with benzene (500 ml.) and acidified with excess concentrated hydrochloric acid. The mixture was shaken and the aqueous phase removed and twice extracted with 100 ml. portions of benzene. The combined benzene extracts were dried over anhydrous sodium sulfate and the solvent evaporated on a steam bath. The solid was dried, yielding 120 g. (70%) of levo-4-(o-chlorobenzyl)-4-phenyl-5-oxohexanoic acid, M.P. 106-109° C. Recrystallization from heptane gave 118.5 g., M.P. 109-110.5° C. A second recrystallization from heptane gave 116.5 g., M.P. 109-110.5° C. The

specific rotation of a 2% solution in 95% ethanol was -143.1° at 25° C.

Example 73.—*Dextro-4-(o-chlorobenzyl)-4-phenyl-5-oxohexanoic acid.*—The methanolic mother liquor from which the brucine salt of the levo-acid separated (described in Example 72) was evaporated to dryness at reduced pressure on a steam bath. The resulting oil was dissolved in chloroform (500 ml.) and extracted with an excess of aqueous sodium hydroxide solution (1 liter containing 28 g., 0.7 mole, of sodium hydroxide). Two more extractions of the chloroform phase with 100 ml. portions of aqueous sodium hydroxide of the same strength were made. The combined aqueous extracts were acidified with excess concentrated hydrochloric acid and the mixture then extracted with benzene (500 ml.). Two more extractions with benzene (100 ml. portions) were made, and then the combined benzene extracts were extracted with aqueous sodium hydroxide solution (1 liter containing 28 g., 0.7 mole, of sodium hydroxide). The aqueous layer was again acidified with excess concentrated hydrochloric acid and extracted with benzene (500 ml.). The benzene solution was dried over sodium sulfate and then the benzene removed by evaporation. The resulting oil consisted of a mixture of the dextro-acid and the racemate. The oil was dissolved in acetonitrile (about 140 ml.) and the solution cooled in the refrigerator overnight. The solid that separated consists mainly of the racemic modification. This material was removed by filtration, and the filtrate was concentrated to dryness. The product solidified upon cooling. The yield was 125 g., M.P. 97-101° C. Recrystallization from heptane gave material melting at 100-103° C. The specific rotation of a 2% solution in 95% ethanol was +127.5° at 25° C.; this represents an optical purity of about 96%. Fractional crystallization from acetonitrile gave material melting at 109-110° C. and a specific rotation of +142.0° for a 2% solution in 95% ethanol at 25° C.

Example 74.—*Levo-4-(o-bromobenzyl)-4-phenyl-5-oxohexanoic acid.*—By replacing racemic-4-(o-chlorobenzyl)-4-phenyl-5-oxohexanoic acid of Example 72 by an equimolecular quantity of racemic-4-(o-bromobenzyl)-4-phenyl-5-oxohexanoic acid, prepared as described in Example 69, and preparing the brucine salt of this latter product by substantially the same process described in Example 72, there was obtained a 57% yield of levo-4-(o-bromobenzyl)-4-phenyl-5-oxohexanoic acid which, after recrystallization from cyclohexane, melted at 85.5-87.5° C. The specific rotation of a 2% solution of this product in 95% ethanol was -118.5° at 25° C.

The racemic modification of the other hexanoic acids described in Examples 49-71 can be separated by the process described in Example 72. Complete examples of the separation of each of them are not included because to do so would only lengthen the disclosure unduly without adding any material teaching to the art.

D. PREPARATION OF DERIVATIVES OF 4-ARYL-4-ARALKYL-5-OXOHEXANOIC ACIDS

D1. ESTERS OF 4-ARYL-4-ARALKYL-5-OXOHEXANOIC ACIDS

Most of the esters of the 4-aryl-4-aralkyl-5-oxohexanoic acids are advantageously prepared by dissolving the selected hexanoic acid in a mixture of absolute alcohol and concentrated sulfuric acid. An advantageous ratio is about 1 mole of the hexanoic acid, 2-2.5 liters of alcohol and 70-85 ml. of concentrated sulfuric acid. The mixture is then refluxed several hours, generally from 3 to 10 hours, under anhydrous conditions and the excess alcohol removed by distillation or evaporation. The residue, containing the crude ester, then is dissolved in about 200 ml. of benzene. The benzene solution is washed 2-5 times with 25 ml. portions of water and then 2-5 times with aqueous sodium bicarbonate. In some cases the ester may be isolated by pouring the reaction mixture into water and dissolving the material that separates in benzene. The benzene solution is dried advantageously over sodium sulfate, and the solvent removed by distillation or evaporation.

The following example describes the above procedure for making esters of 4-aryl-4-aralkyl-5-hexanoic acid in more detail.

Example 75.—*Methyl 4-benzyl-4-phenyl-5-oxohexanoate.*—4-benzyl-4-phenyl-5-oxohexanoic acid (50 g., 0.169 mole), prepared as described in Example 58, was dissolved in absolute methanol (200 ml.), and concentrated sulfuric acid (14 ml.) was added. The mixture was refluxed under anhydrous conditions for 7½ hours. The solution was cooled and poured into a liter of ice water. An oil separated which soon solidified. The solid was filtered off, washed in water, and dissolved in benzene. The solution was washed with water, then with sodium bicarbonate solution, and again with water. The benzene solution was dried over sodium sulfate and the benzene then removed by evaporation, yielding 52 g. (99%) of methyl 4-benzyl-4-phenyl-5-oxohexanoate, M.P. 89-90° C. Further purification by distillation yielded a product having a boiling point of 158-160° C. at 0.5 mm. Upon recrystallization from hexane, the melting point remained essentially unchanged.

Example 76.—*Levo methyl 4-(o-chlorobenzyl)-4-phenyl-5-oxohexanoate.*—Levo-4-(o-chlorobenzyl)-4-phenyl-5-oxohexanoic acid (100 g., 0.3 mole), obtained as described in Example 72, was dissolved in a solution of absolute methanol (400 ml.) and concentrated sulfuric acid (16 ml.). The solution was refluxed under anhydrous conditions for seven hours. Most of the solvent was removed by reduced pressure distillation and the residue poured into water. The mixture was extracted three times with toluene (125 ml. portions) and the combined extracts were washed first with water, then saturated sodium bicarbonate solution and finally with water. After drying over anhydrous sodium sulfate, the solvent was removed by reduced pressure distillation. The residue was fractionally distilled at reduced pressure yield a total of 104 g. (87%) of material boiling at 187-192° at 0.2 mm. pressure. Refractionation gave methyl 4-(o-chlorobenzyl)-4-phenyl-5-oxohexanoate, boiling at 194-199° C. at 0.2 mm. pressure, $n_{D}^{25}=1.5621$.

Other esters of 4-aryl-4-aralkyl-5-oxohexanoic acid, identified in column C of Table IV, were prepared by allowing the hexanoic acid, identified in column A, to react with the alcohol, identified in column B, according to the procedure D1 and Example 75 above.

14

85.	4-benzyl-4-(3,4-dichlorophenyl)-5-oxohexanoic acid (Product of Ex. 51)	do	Methyl 4-benzyl-4-(3,4-dichlorophenyl)-5-oxohexanoate.	
30	86.	4-(3,4,5-trichlorobenzyl)-4-phenyl-5-oxohexanoic acid (Product of Ex. 52)	Ethanol	Ethyl 4-(3,4,5-trichlorobenzyl)-4-phenyl-5-oxohexanoate.
87.	4-(p-propylbenzyl)-4-phenyl-5-oxohexanoic acid (Product of Ex. 53)	1-butanol	1-butyl 4-(p-propylbenzyl)-4-phenyl-5-oxohexanoate.	
35	88.	4-(p-chlorobenzyl)-4-(p-ethylphenyl)-5-oxohexanoic acid (Product of Ex. 54)	Ethanol	Ethyl 4-(p-chlorobenzyl)-4-(p-ethylphenyl)-5-oxohexanoate.
89.	4-(p-ethoxybenzyl)-4-(m-methoxyphenyl)-5-oxohexanoic acid (Product of Ex. 56)	1-propanol	1-propyl 4-(p-ethoxybenzyl)-4-(m-methoxyphenyl)-5-oxohexanoate.	
40				

D2. 1,3-CYCLOHEXANEDIONE DERIVATIVES OF 4-ARYL-4-ARALKYL-5-OXOHEXANOIC ACIDS

The 1,3-cyclohexanenedione derivatives of the 4-aryl-4-aralkyl-5-oxohexanoic acids can be prepared by various methods. The 1,3-cyclohexanenedione derivative is often formed as a by-product when the 4-aryl-4-aralkyl-5-oxohexanenitriles are hydrolyzed to the corresponding acid. The 1,3-cyclohexanenedione by-product may be formed

50 regardless of whether the hydrolysis of the nitrile is conducted under acid or alkaline conditions. The cyclohexanenedione product in general was separated from the hexanoic acid by making use of the difference in their solubility in organic solvents.

55 In addition, the 1,3-cyclohexanenedione derivatives can be prepared from an ester of the 4-aryl-4-aralkyl-5-oxohexanoic acid which is readily converted to the 1,3-cyclohexanenedione in the presence of sodium alkoxide or similar basic catalyst.

60 Another method by which the 1,3-cyclohexanenediones can be prepared is by reaction of the 1-aryl-1-aralkyl-2-propanones with beta-propiolactone in the presence of certain condensing agents, such as potassium tertiary-butoxide. Optimum yields are obtained when an excess 65 of beta-propiolactone and of the condensing agent are used. Very good yields have been obtained by employing a molar ratio of ketone to beta-propiolactone to condensing agent of 1:2.5:2.5.

The following examples describe in more detail the 70 above methods for making the 1,3-cyclohexanenedione compounds.

Example 90.—4-benzyl-4-phenyl-1,3-cyclohexanedione.—A one-liter, three-necked flask was fitted with a dropping funnel, mechanical stirrer, and reflux condenser 75 capped with a drying tube. Absolute ethanol (150 ml.)

and sodium (6.0 g., 0.26 mole) were introduced into the flask. As soon as the sodium had reacted, the excess alcohol was removed by distillation at reduced pressure while anhydrous conditions were maintained, then dry ether (100 ml.) was added. A solution of methyl 4-benzyl-4-phenyl-5-oxohexanoate (50.5 g., 0.163 mole), prepared as described in Example 75, dissolved in ether (400 ml.) was added with stirring. A clear solution resulted, which soon began depositing a solid. After stirring for 18 hours at room temperature, the solution was refluxed for 4 hours. The mixture was cooled and treated with water (300 ml.), which dissolved the solid. The ether layer was separated and extracted with 5% sodium hydroxide (100 ml.). The combined aqueous layers were acidified with excess concentrated hydrochloric acid. The solid that separated was filtered off and washed with water. The yield was 45 g. of 4-benzyl-4-phenyl-1,3-cyclohexanedione, M.P. 178-180° C. After recrystallization, first from acetonitrile and then from ethyl acetate, the product melted at 181-182.5° C.

Example 91.—4-(*o*-chlorobenzyl)-4-(*o*-chlorophenyl)-1,3-cyclohexanedione.—By replacing the methyl 4-benzyl-4-phenyl-5-oxohexanoate employed in Example 90 by an equimolecular quantity of methyl 4-(*o*-chlorobenzyl)-4-(*o*-chlorophenyl)-5-oxohexanoate, product of Example 84, there was obtained 4-(*o*-chlorobenzyl)-4-(*o*-chlorophenyl)-1,3-cyclohexanedione.

Example 92.—4-benzyl-4-(3,4-dichlorophenyl)-1,3-cyclohexanedione.—By replacing the methyl 4-benzyl-4-phenyl-5-oxohexanoate employed in Example 90 by an equimolecular quantity of methyl 4-benzyl-4-(3,4-dichlorophenyl)-5-oxohexanoate, product of Example 85, there was obtained 4-benzyl-4-(3,4-dichlorophenyl)-1,3-cyclohexanedione.

Example 93.—4-(*p*-propylbenzyl)-4-phenyl-1,3-cyclohexanedione.—By replacing the methyl 4-benzyl-4-phenyl-5-oxohexanoate employed in Example 90 by an equimolecular quantity of 1-butyl 4-(*p*-propylbenzyl)-4-phenyl-5-oxohexanoate, product of Example 87, there was obtained 4-(*p*-propylbenzyl)-4-phenyl-1,3-cyclohexanedione.

Example 94.—4-(*p*-chlorobenzyl)-4-(*p*-ethylphenyl)-1,3-cyclohexanedione.—By replacing the methyl 4-benzyl-4-phenyl-5-oxohexanoate employed in Example 90 by an equimolecular quantity of ethyl 4-(*p*-chlorobenzyl)-4-(*p*-ethylphenyl)-5-oxohexanoate, product of Example 88, there was obtained 4-(*p*-chlorobenzyl)-4-(*p*-ethylphenyl)-1,3-cyclohexanedione.

Example 95.—4-(*p*-ethoxybenzyl)-4-(*m*-methoxyphenyl)-1,3-cyclohexanedione.—By replacing the methyl 4-benzyl-4-phenyl-5-oxohexanoate employed in Example 90 by an equimolecular quantity of 1-propyl 4-(*p*-ethoxybenzyl)-4-(*m*-methoxyphenyl)-5-oxohexanoate, product of Example 89, there was obtained 4-(*p*-ethoxybenzyl)-4-(*m*-methoxyphenyl)-1,3-cyclohexanedione.

Example 96.—4-(*o*-chlorobenzyl)-4-phenyl-1,3-cyclohexanedione.—In a two-liter, four-necked, round-bottom flask fitted with a reflux condenser (protected with a drying tube), thermometer, dropping funnel, and mechanical stirrer was placed dry tertiary-butyl alcohol (700 ml.), and metallic potassium (19.5 g., 0.5 mole) was added. With vigorous stirring at reflux, the potassium reacted quickly. The solution was cooled to 25° C. and 1-(*o*-chlorobenzyl)-1-phenyl-2-propanone (129.4 g., 0.5 mole), product of Example 1, was added and washed in with tertiary-butyl alcohol (50 ml.). Beta-propiolactone (36.0 g., 0.5 mole) in tertiary-butyl alcohol (100 ml.) was added dropwise over 1 hour at 25-28° C. The mixture was refluxed on a steam bath for 1½ hours; then the solvent was removed by distillation at reduced pressure. The viscous residue was treated with water (500 ml.) and benzene (250 ml.) with vigorous stirring. The layers were separated and the aqueous layer extracted with benzene (100 ml.). The combined organic layers

were extracted with water (50 ml.), and the combined aqueous extracts were acidified with dilute hydrochloric acid. An oily product solidified upon stirring. After drying, 63.2 g. (40%) of crude 4-(*o*-chlorobenzyl)-4-phenyl-1,3-cyclohexanedione was obtained. Recrystallization from acetic acid (125 ml.) gave material melting at 156-159° C. After two additional recrystallizations from acetonitrile, the product melted at 158-160.5° C.

Example 97.—4-(*o*-methylbenzyl)-4-phenyl-1,3-cyclohexanedione.—A solution of potassium tertiary-butoxide was prepared by allowing potassium (6.6 g., 0.169 mole) to react with dry tertiary-butyl alcohol (175 ml.) under anhydrous conditions. While stirring, the solution was treated with 1-(*o*-methylbenzyl)-1-phenyl-2-propanone (16.1 g., 0.0677 mole), obtained as described in Example 19, in tertiary-butyl alcohol (25 ml.). A solution of beta-propiolactone (12.2 g., 0.169 mole) in tertiary-butyl alcohol (50 ml.) was added, dropwise with stirring, over 15 minutes. The temperature was kept at 38-42° C. during the addition by cooling when necessary.

After the addition was complete, the mixture was refluxed for 2 hours and the solvent then was removed by distillation at reduced pressure. The residue was treated with water (150 ml.) and benzene (75 ml.). After shaking, the layers were separated. The benzene layer was extracted with 5% potassium hydroxide (100 ml.). The combined aqueous extracts were treated with decolorizing charcoal, filtered and acidified with concentrated hydrochloric acid. The oil that separated soon solidified. The solid was removed by filtration and washed with a small amount of hexane. The yield of crude product was 14.9 g. (75%). Two recrystallizations from a small volume of acetonitrile gave 4-(*o*-methylbenzyl)-4-phenyl-1,3-cyclohexanedione melting at 177-179° C.

Other 1,3-cyclohexanedione derivatives, which were obtained either as byproducts during the hydrolysis of the 4-aryl-4-alkyl-5-oxohexanenitriles to the corresponding carboxylic acids or by the reaction of a 1-aryl-1-alkyl-2-propanone with beta-propiolactone, are identified in the following Table V.

Table V

Ex.	R	R'	Reaction method	M.P.° C.
50	Phenyl	m-Methylbenzyl	Prepared by the process described in Example 97.	168-169.5
98	do	p-Chlorobenzyl	By-product of acid hydrolysis described in Example 62.	220-221.5
55	100	3,4-dichlorobenzyl	By-product of acid hydrolysis described in Example 64.	172-173
101	do	o-Bromobenzyl	By-product of acid hydrolysis described in Example 69.	154.5-156
60				

D. ENOL-LACTONES OF 4-ARYL-4-ARALKYL-5-OXOHEXANOIC ACIDS

The enol-lactone derivatives are made as follows: A mixture of the selected hexanoic acid, isopropenyl acetate, and a few drops of concentrated sulfuric acid is placed in a flask equipped with a long fractionating column connected to a downwardly directed condenser. The mixture is heated with a mantle so that the acetone that is formed is continuously removed by distillation. This process is continued for 2-3 hours, and the residue then is transferred to a flask suitably equipped for distillation at reduced pressure. After distillation of the by-products and unreacted isopropenyl acetate, the enol-lactone can be iso-

lated from the undistilled residue or it can be purified by distillation.

The following example is a detailed procedure for making the enol-lactone derivatives by the above method.

Example 102. — 4-(o-chlorobenzyl)-4-phenyl-5-hydroxy-5-hexenoic acid lactone. — 4-(o-chlorobenzyl)-4-phenyl-5-oxohexanoic acid (82.7 g., 0.25 mole), product of Example 49, isopropenyl acetate (75.1 g., 0.75 mole), and concentrated sulfuric acid (3 drops) were placed in a flask with a long fractionating column connected to a downwardly directed condenser. The mixture was heated by means of a mantle over a period of 2 hours so that a slow distillation occurred. A total of 33.5 ml. of distillate boiling at 55-59° C. was collected. This material was discarded and the residue distilled at reduced pressure. A yield of 66 g. (78%) of 4-(o-chlorobenzyl)-4-phenyl-5-hydroxy-5-hexenoic acid lactone, B.P. 196-204° C. at 0.1 mm. pressure, M.P. 126-132° C. was obtained. Upon recrystallization from toluene and then hexane, the product melted at 134.5-136° C.

Example 103. — Levo-4-(o-chlorobenzyl)-4-phenyl-5-hydroxy-5-hexenoic acid lactone. — Isopropenyl acetate (100 g., 1 mole) and levo-4-(o-chlorobenzyl)-4-phenyl-5-oxohexanoic acid (80 g., 0.24 mole), obtained as described in Example 72, were placed in a flask equipped with a long fractionating column and concentrated sulfuric acid (3 drops) was added. A downwardly directed condenser was attached to the side arm and the mixture was gently heated so that a slow distillation occurred. A total of 30 ml. of material, boiling at 56-59° C., was collected during two hours. Another drop of concentrated sulfuric acid was added to the reaction mixture and heating was continued for another 30 minutes; however, only a very little more distillate was collected.

Volatile materials were removed by distilling the residue on a steam bath at reduced pressure. The residue then was fractionated in an ordinary Claisen flask. A total of 63 g. (84%) of material, boiling at 205-212° C. at 0.2 mm., was collected. The product was fractionated a second time and the solid which formed on standing was recrystallized first from cyclohexane then twice from heptane. Levo-4-(o-chlorobenzyl)-4-phenyl-5-hydroxy-5-hexenoic acid lactone was obtained as a crystalline product melting at 113-113.5° C. (uncorr.), the specific rotation of a 3% solution in toluene at 25° C. was -382.2°.

Other compounds, identified in Table VI below, were prepared by the above described method. The starting materials are identified in column 2, and the enol-lactone produced is identified in column 3.

Table VI

Ex.	Starting material	Enol-lactone
104...	4-(o-bromobenzyl)-4-phenyl-5-oxohexanoic acid (Product of Ex. 69).	4-(o-bromobenzyl)-4-phenyl-5-hydroxy-5-hexenoic acid lactone.
105...	4-(m-methylbenzyl)-4-phenyl-5-oxohexanoic acid (Product of Ex. 61).	4-(m-methylbenzyl)-4-phenyl-5-hydroxy-5-hexenoic acid lactone.
106...	4-(o-fluorobenzyl)-4-phenyl-5-oxohexanoic acid (Product of Ex. 63).	4-(o-fluorobenzyl)-4-phenyl-5-hydroxy-5-hexenoic acid lactone.
107...	4-(2,6-dichlorobenzyl)-4-phenyl-5-oxohexanoic acid (Product of Ex. 66).	4-(2,6-dichlorobenzyl)-4-phenyl-5-hydroxy-5-hexenoic acid lactone.
108...	4-(m-chlorobenzyl)-4-phenyl-5-oxohexanoic acid (Product of Ex. 68).	4-(m-chlorobenzyl)-4-phenyl-5-hydroxy-5-hexenoic acid lactone.
109...	4-benzyl-4-(o-chlorophenyl)-5-oxohexanoic acid (Product of Ex. 71).	4-benzyl-4-(o-chlorophenyl)-5-hydroxy-5-hexenoic acid lactone.
110...	4-(3,4-dichlorobenzyl)-4-(4-chlorophenyl)-5-oxohexanoic acid (Product of Ex. 50).	4-(3,4-dichlorobenzyl)-4-(4-chlorophenyl)-5-hydroxy-5-hexenoic acid lactone.
111...	4-(p-propylbenzyl)-4-phenyl-5-oxohexanoic acid (Product of Ex. 53).	4-(p-propylbenzyl)-4-phenyl-5-hydroxy-5-hexenoic acid lactone.

Table VI—Continued

Ex.	Starting material	Enol-lactone
5 112...	4-(o-chlorobenzyl)-4-(p-methoxyphenyl)-5-oxohexanoic acid (Product of Ex. 55).	4-(o-chlorobenzyl)-4-(p-methoxyphenyl)-5-hydroxy-5-hexenoic acid lactone.
113...	4-(m-methylbenzyl)-4-(o-methoxyphenyl)-5-oxohexanoic acid (Product of Ex. 57).	4-(m-methylbenzyl)-4-(o-methoxyphenyl)-5-hydroxy-5-hexenoic acid lactone.
114...	4-(o-chlorobenzyl)-4-(o-chlorophenyl)-5-oxohexanoic acid (Product of Ex. 70).	4-(o-chlorobenzyl)-4-(o-chlorophenyl)-5-hydroxy-5-hexenoic acid lactone.
10 115...	4-benzyl-4-(3,4-dichlorophenyl)-5-oxohexanoic acid (Product of Ex. 51).	4-benzyl-4-(3,4-dichlorophenyl)-5-hydroxy-5-hexenoic acid lactone.
116...	4-(3,4,5-trichlorobenzyl)-4-phenyl-5-oxohexanoic acid (Product of Ex. 52).	4-(3,4,5-trichlorobenzyl)-4-phenyl-5-hydroxy-5-hexenoic acid lactone.
15 117...	4-(p-chlorobenzyl)-4-(p-ethylphenyl)-5-oxohexanoic acid (Product of Ex. 54).	4-(p-chlorobenzyl)-4-(p-ethylphenyl)-5-hydroxy-5-hexenoic acid lactone.
118...	4-benzyl-4-phenyl-5-oxohexanoic acid (Product of Ex. 58).	4-benzyl-4-phenyl-5-hydroxy-5-hexenoic acid lactone.
119...	4-(3,4-dichlorobenzyl)-4-phenyl-5-oxohexanoic acid (Product of Ex. 64).	4-(3,4-dichlorobenzyl)-4-phenyl-5-hydroxy-5-hexenoic acid lactone.

D4. BASIC ESTERS OF 4-ARYL-4-ARALKYL-5-OXOHESANOIC ACIDS

The basic esters of the hexanoic acids of this invention are readily prepared by first converting the desired 4-aryl-4-alkyl-5-oxohexanoic acid to the corresponding enol-lactone by the procedure described in D3 above and then heating the enol-lactone with the desired (di-substituted-amino)-alkanol, which is generally used in excess. The enol-lactone can be dissolved in the selected (di-substituted-amino)-alkanol when the alkanol is a liquid, and in the event the alkanol is a solid, then the alkanol can be melted and the enol-lactone dissolved therein or the enol-lactone and the (di-substituted-amino)-alkanol can be dissolved in a common inert solvent. The solution, however made, is then heated preferably under anhydrous conditions and often conveniently refluxed for several hours. The excess (di-substituted-amino)-alkanol then is distilled off and the residue, the basic ester, purified according to conventional methods.

The following example describes the process for making the basic esters of the hexanoic acids of this invention in more detail.

Example 120. — 2-dimethylaminoethyl 4-(o-chlorobenzyl)-4-phenyl-5-oxohexanoate hydrobromide. — 4-(o-chlorobenzyl)-4-phenyl-5-hydroxy-5-hexenoic acid lactone (36.1 g., 0.115 mole), product of Example 102, was dissolved in dry 2-dimethylaminoethanol (89 g., 1.0 mole) and the mixture heated under anhydrous conditions for 30 minutes at 95° C. and then refluxed for 2 hours. The excess amine was removed by distillation at reduced pressure and the residue dissolved in benzene (250 ml.). The solution was washed twice with water and then dried over sodium sulfate. The solvent was removed by distillation at reduced pressure and the residue dissolved in cyclohexane (150 ml.).

Dry hydrogen bromide was passed through the solution until precipitation no longer occurred. The precipitated product was a sticky, semi-solid material. Addition of benzene (50 ml.) and kneading the mixture produced a white solid. The solid was filtered off and washed with a solution of 10% benzene in cyclohexane. The product was dried in a vacuum desiccator over phosphorus pentoxide (P_2O_5). The yield of dry 2-dimethylaminoethyl 4-(o-chlorobenzyl)-4-phenyl-5-oxohexanoate hydrobromide was 48.2 g. (87%), M.P. 144-148° C. Recrystallization from isopropyl alcohol (150 ml.) gave 43.6 g., M.P. 149-151° C. A second recrystallization gave 41.7 g., M.P. 149-151° C.

Other basic esters, identified in column 5 of Table VII, were prepared according to the above procedure using the enol-lactone identified in column 2 and the (di-substituted-amino)-alkanol identified in column 4 with or without an inert solvent and heating the mixture, thus producing the basic ester identified in column 5.

Table VII

Ex. No.	Enol-lactone	Enol- lactone of Ex- ample No.	(Disubstituted-amino) alkanol	Basic ester
121	4-(o-bromobenzyl)-4-phenyl-5-hydroxy-5-hexenoic acid lactone.	104	2-dimethylaminoethanol.....	2-dimethylaminoethyl 4-(o-bromobenzyl)-4-phenyl-5-oxohexanoate hydrobromide.
122	4-(m-methylbenzyl)-4-phenyl-5-hydroxy-5-hexenoic acid lactone.	105	2-diethylaminoethanol.....	2-diethylaminoethyl 4-(m-methylbenzyl)-4-phenyl-5-oxohexanoate hydrobromide.
123	4-(o-fluorobenzyl)-4-phenyl-5-hydroxy-5-hexenoic acid lactone.	106	2-dimethylaminoethanol.....	2-dimethylaminoethyl 4-(o-fluorobenzyl)-4-phenyl-5-oxohexanoate hydrobromide.
124	4-(2,6-dichlorobenzyl)-4-phenyl-5-hydroxy-5-hexenoic acid lactone.	107	3-diethylamino-1-propanol.....	3-diethylamino-1-propyl 4-(2,6-dichlorobenzyl)-4-phenyl-5-oxohexanoate hydrobromide.
125	4-(m-chlorobenzyl)-4-phenyl-5-hydroxy-5-hexenoic acid lactone.	108	.....do.....	3-diethylamino-1-propyl 4-(m-chlorobenzyl)-4-phenyl-5-oxohexanoate hydrobromide.
126	4-benzyl-4-(o-chlorophenyl)-5-hydroxy-5-hexenoic acid lactone.	109	4-dimethylamino-1-butanol.....	4-dimethylamino-1-butyl 4-benzyl-4-(o-chlorophenyl)-5-oxohexanoate hydrobromide.
127	4-(o-chlorobenzyl)-4-(o-chlorophenyl)-5-hydroxy-5-hexenoic acid lactone.	114	2-diethylaminoethanol.....	2-diethylaminoethyl 4-(o-chlorobenzyl)-4-(o-chlorophenyl)-5-oxohexanoate anhydriodobromide.
128	4-benzyl-4-(3,4-dichlorophenyl)-5-hydroxy-5-hexenoic acid lactone.	115	3-diethylamino-1-propanol.....	3-diethylamino-1-propyl 4-benzyl-4-(3,4-dichlorophenyl)-5-oxohexanoate hydrobromide.
129	4-(3,4,5-trichlorobenzyl)-4-phenyl-5-hydroxy-5-hexenoic acid lactone.	116	2-dimethylaminoethanol.....	2-dimethylaminoethyl 4-(3,4,5-trichlorobenzyl)-4-phenyl-5-oxohexanoate hydrobromide.
130	4-(p-chlorobenzyl)-4-(p-ethylphenyl)-5-hydroxy-5-hexenoic acid lactone.	117	3-diethylamino-1-butanol.....	3-diethylamino-1-butyl 4-(p-chlorobenzyl)-4-(p-ethylphenyl)-5-oxohexanoate hydrobromide.
131	4-(o-chlorobenzyl)-4-(p-methoxyphenyl)-5-hydroxy-5-hexenoic acid lactone.	112	3-dipropylamino-1-propanol.....	3-dipropylamino-1-propyl 4-(o-chlorobenzyl)-4-(p-methoxyphenyl)-5-oxohexanoate hydrobromide.
132	4-(3,4-dichlorobenzyl)-4-phenyl-5-hydroxy-5-hexenoic acid lactone.	119	4-dimethylamino-1-butanol.....	4-dimethylamino-1-butyl 4-(3,4-dichlorobenzyl)-4-phenyl-5-oxohexanoate hydrobromide.

D5. AMIDES OF 4-ARYL-4-ARALKYL-5-OXOHEXANOIC ACIDS

The amides are advantageously prepared by first converting the hexanoic acids to the corresponding enol-lactone according to the procedure described in D3 and then heating the enol-lactone with the desired amine. The reactants often are advantageously refluxed under anhydrous conditions. An inert solvent or an excess of the selected amine can be employed as a solvent in the reaction.

The amides identified in column 5 of Table VIII were prepared by reacting the enol-lactone identified in column 2 with the (di-substituted-amino)-alkylamine identified in column 4 according to the above described procedure.

While the invention has been illustrated by particular 4-aryl-4-alkyl-5-oxohexanoic acids and particular representative derivatives thereof, and particular methods for 35 the preparation of each of these groups of compounds, the invention embraces the chemical equivalents of the specifically identified compounds, many of which have been prepared but have not been specifically enumerated for 40 the sake of clarity and brevity, as well as other known methods which could be employed in the preparation of the various compounds described hereinbefore and their chemical equivalents.

What is claimed is:

45 1. A 4,4-disubstituted-5-oxohexanoic acid having the
